Primary Examiner — Cynthia M Chin(74) *Attorney, Agent, or Firm* — Williams Intellectual Property; Benjamin F. Williams(57) **CLAIM**

The ornamental design for a sledding cart, as shown and described.

DESCRIPTION

FIG. 1 is a front isometric view of a voluble sledding cart illustrating a scooped seat adjustably positional atop a single frame bar and a pivotal front wheel steering bar;
FIG. 2 is a front elevation view of the voluble sledding cart;
FIG. 3 is a rear isometric view of the voluble sledding cart;
FIG. 4 is a side elevation view of the voluble sledding cart;
FIG. 5 is a side elevation view of the voluble sledding cart;
FIG. 6 is a top elevation view of the voluble sledding cart;
and,
FIG. 7 is a bottom elevation view of the voluble sledding cart.
